CLAMPING DEVICE FOR PORCELAIN SHELLS

Edwin E. Arnold, Pittsburgh, Pa., and John H. Chiles, Jr., Sharon, Pa., assignors to Westinghouse Electric & Manufacturing Company, East Pittsburgh, Pa., a corporation of Pennsylvania

Application December 13, 1939, Serial No. 309,038

3 Claims. (Cl. 174—163)

Our invention relates to means for clamping a ceramic body to another body and particularly to means for clamping a porcelain shell such as used in the electric insulator art to a base, a cap or an adjacent porcelain.

The means for accomplishing this as taught by the prior art comprise securing a flange to the porcelain and bolting the flange to the piece to which the porcelain is to be clamped. This method presents serious disadvantages. In the first place the difference in the coefficient of expansion of the flange metal and porcelain will highly stress the porcelain shell and may cause it to rupture. In addition, the heavy flange section when drawn down may place undue stress on the porcelain due to the leverage action of the flange.

It is, accordingly, an object of our invention to provide new and improved means for clamping a ceramic body to another body.

Another object of our invention is to provide means for clamping a porcelain shell to another body in such a manner that no excessive stress is put upon the porcelain shell or its connection with the clamping means.

It is a further object of our invention to provide a gasket arrangement and a clamping means for securing a porcelain shell to another body in such manner that a predetermined pressure may be exerted upon the gasket without the porcelain shell being subjected to any excessive or unbalanced stress.

Other objects of our invention will become evident from the following detailed description, taken in conjunction with the accompanying drawing in which:

Figure 1 is a view partly in section of a means taught by the prior art for connecting a porcelain shell to a metal member.

Fig. 2 is a view in section of a portion of a connection made in accordance with a preferred form of our invention.

Fig. 3 is an enlarged view in section showing the gasket of Fig. 2 in stressed condition; and,

Figs. 4, 5, 6, 7 and 8 are views in section of portions of connections made in accordance with modifications of our invention.

Throughout the drawing corresponding parts are designated by the same numerals followed by different alphabetic characters. In the prior art construction shown in Fig. 1, the porcelain shell 1 is seated on the annular gasket 2 disposed on the base 3 which may be a portion of a housing for electrical apparatus. The gasket 2 extends across only a portion of the thickness of the shell 1 while a gasket stop 4 of non-compressible ma-

terial is provided to limit the compression thereof. An annular metallic flange 5 is attached to the shell 1 by cement 6 and secured to the base 3 by bolts 7. It will readily appear that with this construction that the porcelain and cement at the upper portion of the flange 5 as at A will be subjected to considerable tensile stress while the lower portions thereof will be under compression at B.

Another disadvantage of this prior art construction lies in the fact that when the gasket 2 is first compressed, all the pressure is concentrated on the porcelain surface in contact therewith. After the porcelain contacts the stop 4 the pressure across the face will change, and, depending on how tightly the porcelain is drawn down, it may become excessive over the stop area.

In the embodiment of our invention shown in Fig. 2 a porcelain shell designated by 8 has a metallic flange 9 secured thereto by cement 10. At a plurality of points, the flange 9 is tapped at an angle with the vertical as at 11 and screw threaded to receive bolts 12 extending through the annulus 13, the inner periphery of which fits against the annular shoulder 14 of the base member 15. The annulus 13 is preferably of two-piece spring construction and bent to form a partly conical outer portion at 16 to provide flat seats for the heads of the bolts 12. An annular groove 17 of somewhat greater width than the thickness of the shell 8 is provided in the base 15 and a gasket 18 which may be of a deformable but not necessarily compressible material is seated therein to receive the edge of the shell 8. An auxiliary groove 19 may be formed within the groove 17 to further control the sealing characteristics of the gasket 18.

It will become obvious that an effect of applying the force in an angular direction in the preferred embodiment of Fig. 2 is to eliminate the undesirable turning moment produced in the prior art construction of Fig. 1.

The gasket 18 being of full width will result in the pressure upon the shell 8 being evenly distributed and it may be maintained at a constant predetermined value since the annulus 13 has spring characteristics. Similar results may be obtained with a rigid annulus if the heads of the bolts are seated hereagainst through other suitable means hereinafter described, such as helical springs.

The groove 17, in addition, supports the gasket against sidewise displacement and the rounded edges of the shell 8 prevent stress con-

centration at the boundary zones of contact with the gasket 18. The auxiliary grooving 19 provides means for regulating the effective gasket area and, in fact, such grooving may be useful where a main groove 17 is not provided. This action of the gasket 18 will be more readily understood from Fig. 3 which is a view of the gasket arrangement of Fig. 2 when under compression. The same members are indicated by the same numerals in the two figures.

In the modification of our invention shown in Fig. 4, the shell 8a has a metallic band 20 on which is formed a projecting portion 21 cemented thereto as at 22. An annular flange member 23 is attached to the base member 24 by bolts 25 and engages the projecting portion 21 of the band 20 to maintain the shell 8a in position. A spring 26 is provided between the head of each bolt 25 and the base 24 to provide a predetermined fixed pressure between the shell 8a and the gasket 18a which is shown in compressed condition. The spring may be placed at the other end of the bolt 25 or one may be employed at each end if desired. Preferably a softening gasket 27 is provided between the projecting portion 21 and the flange member 23. The gasket 18a and the structure cooperating therewith is similar to that shown in Figs. 2 and 3.

In this structure of Fig. 4, the flange does not exert the leverage action of the prior art structure of Fig. 1. In addition to the length of the lever arm being considerably reduced, it is possible to vary the shape of band 20 and the position of the projecting portion 21 so as to grade the tension and compression effects at the ends of the cemented portion 22.

The construction of Fig. 5 differs from Fig. 3 in that the porcelain shell 8b is attached to the base through a pair of annular members 28 and 29 drawn together by means of bolts 25b. The upper member 28 which preferably comprises two spring portions contacts the projecting portion 21b of the band 20b through softening gasket 27b while the lower annulus 29 also has spring characteristics and seats at its inner periphery against a shoulder 14b in the base 15b. It will be obvious that the desired spring pressure may be obtained by making only one of the annular members 28 and 29 of spring construction. In fact, springs such as shown in Fig. 4 as well as any other suitable spring arrangement may be employed to obtain a predetermined pressure on the gasket even where annuli 28 and 29 do not have spring properties.

The embodiment of our invention shown in Fig. 6 differs from that of Fig. 5 in that no metal band is required since the porcelain shell 8c carries a flanged portion 30 integral therewith. A gasket 31 is employed on the portion 30 at its surface of contact with the annular member 28c forming with the annular spring member 29c and bolts 25c an assembly similar to that shown in Fig. 5.

In Fig. 7 an annular spring member 29d seats against the shoulder 14d and supports one end of each of the bolts 25d. The remainder of this assembly is similar to that of Fig. 4.

The modification shown in Fig. 8 comprises a porcelain shell 8e carrying a band 20e cemented thereto as at 22e. A ring member 30 carries a flange 34 which acts against the upper surface of band 20e through a gasket 27e. A two piece spring annulus 29e fits against the shoulder 14e and carries bolts 25e which engage in screw-

threaded holes 32 in ring 33. The construction and arrangement of the gasket 18e is the same as in the other forms shown. It will be noted that in this modification there is no lever action 5 within the structure comprising the shell 8e, ring 29e and cement 22e.

The use of annular members such as 29 (Fig. 5) engaging the base member is of particular advantage in those cases where the base is of 10 ceramic or other non-metallic material which may lack the strength required to support the bolt directly.

Although we have shown and described certain specific embodiments of our invention, we 15 are fully aware that many modifications thereof are possible. The invention therefore is not to be restricted except insofar as is necessitated by the prior art and by the spirit of the appended claims.

20 We claim as our invention:

1. An assembly comprising a ceramic shell, a base member having a continuous groove of substantially the same shape as, but wider than, the edge of said shell and having a second narrower continuous groove at the bottom of said first groove spaced from the edges thereof, resilient gasket means disposed in said first groove in a position bridging said second groove and with said shell seated thereon, projecting means carried by said body, and means including a spring member engaging said projecting means for resiliently clamping said shell to said base member.

2. An assembly comprising a ceramic shell, a base member, resilient gasket means disposed 25 between an edge of said shell and said base member, said gasket means being of a width substantially equal to that of said edge of said shell, said base member having a groove extending over a portion only of the width of its contact 30 surface with said gasket means so as normally to be bridged thereby, annular projection means disposed on the exterior of said shell, annular shoulder means on said base member, a pair of annular plate members, the inner edge of one of 35 said annular members engaging a surface of said projection means opposite said base member and the other of said annular members engaging said shoulder means, at least one of said annular members having spring characteristics, and radially 40 spaced means for clamping said annular members together at the outer edges thereof to secure said shell and base member together in a resilient manner.

3. An assembly comprising a ceramic shell, a base member, resilient gasket means disposed 45 between an edge of said shell and said base member, said gasket means being of a width substantially equal to that of said shell, said base member having at its contact surface with said gasket a continuous groove which is of narrower width 50 than said gasket and is normally bridged thereby, a metallic band secured to said shell, means on said band for gripping a plurality of radially spaced bolt members disposed at an angle with the axis thereof, bolts secured in said gripping means, an annular shoulder portion on said base member, and an annular resilient plate member 55 with its inner edge in engagement with said shoulder portion and its outer edge in engagement with said bolts to secure said shell and said base member together in a resilient manner.
